Atty.

UNITED STATES PATENT OFFICE.

FRANK W. NIGHTINGALE, OF QUINCY, MASSACHUSETTS.

MALLET.

Application filed March 12, 1928. Serial No. 260,966.

This invention relates to mallets of that character in which a head of relatively soft material, such as lead, is provided at one end with a striking member of harder material, such as brass or other composition metal, and with a handle of harder material than lead extended into said head between its ends.

For purposes of the present invention the head of softer material will be referred to as the lead member of the mallet and the striking member as the hard metal member of said mallet.

The present invention has for its object to provide a superior mallet of the character described and one with which a severe blow may be struck with the hard metal member without distortion or displacement of the lead member.

To this end, the hard metal member is provided with a member which projects from its inner surface into the lead member and is made of sufficient length to engage the handle of the mallet within the lead member, so that when a blow is struck with the hard metal member the shock is transmitted to the handle and movement of the striking member with relation to the lead member and distortion of the latter are prevented.

The projecting member may and preferably will be provided with longitudinally extended ribs which serve to effectively lock the lead member to the striking member.

These and other features of the invention will be pointed out in the claims at the end of this specification.

Fig. 1 is an elevation of a mallet embodying this invention;

Fig. 2, a longitudinal section of the mallet shown in Fig. 1, with a portion of the handle omitted, and

Fig. 3, a detail of the harder striking member shown in Figs. 1 and 2.

Referring to the drawing *a* represents the head and *b* the handle of a mallet embodying this invention.

The head *a* is composed of a member 10 of lead or like relatively soft metal, and a member 12 of relatively harder metal than the member 10, such as brass or other composition of metals and the handle *b* is of a material harder than the soft metal member 10.

The member 12 is preferably made as herein shown and is provided with a hollow body portion 14, which is closed at one end by a head 15 and is open at its other end.

The head 15 has extended from its inner surface a projection or member 16 of greater length than the length of the body portion 14 and of sufficient length to engage the handle *b* which is extended into the lead member transversely thereof between the ends of the latter.

The projection or member 16 will be hereinafter referred to as a bearing member, and it is preferably made tapering and provided with longitudinally extended ribs 17 and concaved at its outer end as shown in Fig. 3 to fit the handle *b* when the latter is of cylindrical shape as herein shown.

The handle is preferably a piece of iron or steel pipe having its inner end extended into the lead member and closed at its end by a suitable plug 30.

The body portion 14 of the hard metal member is provided with a plurality of holes 18 for the reception of pins 19 which extend into the hollow body portion and serve as means for locking the soft metal member and the striking member together.

The handle may also be provided with a pin 31 extended through it and projecting into the body portion of the lead member and serving as means for locking the handle to the lead member.

In the manufacture of the handle the hard metal member is placed in a suitable mold, not shown, and molten lead is poured into the mold and fills the hollow body portion of the hard metal member, surrounding the bearing member and interlocking with the ribs 17 of the latter.

The mold is suitably shaped so that the molten lead, when set, forms a continuation of the outer surface of the hollow body portion 14 of the hard metal member, as represented in Fig. 2, and the inner end of the body portion co-operates with a shoulder 20 formed in the lead member 10.

By reference to Fig. 2, it will be seen that the bearing member 16 engages the handle *b*, and when the mallet is used with the hard metal member striking a hard metal object, the shock or blow is transmitted to the handle and movement of the hard metal member with relation to the lead member of the mallet is prevented, consequently a more severe blow may be struck with the hard metal member than when the bearing member is omitted.

In the absence of the bearing member, the shock or blow on the hard member causes

- a displacement of the lead member with relation to the hard metal striking member, and in time the body portion of the metal member would work down over the outside 5 of the hollow body portion 14 of the striking member and be thereby distorted to such extent as to render the hammer in time unsightly and inoperative under certain conditions of use, as, for instance, where 10 it is desired to strike an object close to a surrounding object, which might be hit by the overlapping portion of the lead member before the hard striking member was brought into operative position.
- 15 A mallet of the character described is especially useful in garages and like places, for all uses to which a lead mallet is now used, and in addition is also useful for striking a more solid or harder blow with 20 the striking member 12 of harder material without distortion of the lead member.

In garages the lead member 10 may be used for striking tires and shoes when they stick to the rim of a wheel as the soft metal 25 will not injure the shoe or tire, while the harder metal member may be used for striking bolts and other steel objects, and by transmitting the blow to the handle through the hard metal bearing member 16, a more 30 severe blow may be struck and distortion of the lead member avoided.

It is preferred to use a bearing member having longitudinal ribs as by so doing the 35 ribs may be used to effect an interlocking of the lead member with the bearing member, but it is not desired to limit the invention in this respect.

While it may be preferred to provide the 40 striking member of cylindrical shape as herein shown, it is not desired to limit the invention in this respect.

What is claimed is:

1. In a mallet, in combination, a head of 45 relatively soft material having a striking face at one end thereof and provided with a handle of harder material than said head extended into said head transversely thereof between its ends, a striking member of harder material at the opposite end of said head and provided with a bearing member 50 extended into said head and co-operating with said handle to transmit the force of the

blow upon the harder striking member to said handle and resist relative movement of said harder striking member and said softer head.

2. In a mallet, in combination, a head of 55 relatively soft material having a striking face at one end thereof and provided with a handle of harder material than said head extended into said head transversely thereof between its ends, a striking member of harder material at the opposite end of said head, said striking member having a hollow body portion surrounding a reduced end 60 portion of the softer head and provided with a bearing member of hard material extended into the said head and co-operating with the handle within the said head to engage the same and resist relative movement of the harder striking member and the softer head.

3. In a mallet, in combination, a head of 65 relatively soft material having a striking face at one end thereof and provided with a handle of harder material than said head extended into said head transversely thereof and between its ends, a striking member of harder material at the opposite end of said head, said striking member having a hollow body portion surrounding a reduced end 70 portion of the softer head and provided with a bearing member of hard material extended into the said head and engaged with the handle within the latter and provided with devices for interlocking with the head of softer material.

4. In a mallet, in combination, a head of 75 lead provided with a handle of harder material than lead extended into said head transversely thereof between its ends, a striking member of harder metal at one end of said head and provided with a hollow body portion into which said end of the lead head is extended, and with a bearing member of hard metal extended from the bottom of said hollow body portion out thereof and into the lead head to engage the handle, and means for locking said hollow body portion to the end of the lead head 80 within the same.

In testimony whereof, I have signed my name to this specification.

FRANK W. NIGHTINGALE.
